Patented Oct. 19, 1915.

UNITED STATES PATENT OFFICE.

CHARLES L. BLODGETT, OF ALAMEDA, CALIFORNIA.

CLOTHES-LINE PULLEY.

1,157,143.

Specification of Letters Patent.

Patented Oct. 19, 1915.

Application filed September 24, 1914. Serial No. 863,355.

To all whom it may concern:

Be it known that I, CHARLES L. BLODGETT, a citizen of the United States of America, residing at Alameda, in the county of Alameda and State of California, have invented 5 certain new and useful Improvements in Clothes-Line Pulleys, of which the following is a specification, reference being had therein to the accompanying drawing.

10 This invention relates to clothes line pulleys, and has for its object the production of a simple and efficient means, whereby the line may be held upon the pulley so as to be prevented from jumping off the pulley 15 and become entangled with the support for the pulley.

Another object of the invention is the production of a simple and efficient yoke and means for supporting the same in connection 20 with a pulley to act as a guide or protector for the clothes line cable adapted to pass over the pulley.

With these and other objects in view this invention consists of certain novel combinations, constructions, and arrangements of 25 parts as will be hereinafter fully described and claimed.

In the accompanying drawing:—Figure 1 is a perspective view of the pulley in operation. Fig. 2 is a central vertical section therethrough. Fig. 3 is a central horizontal section therethrough. Fig. 4 is a detail perspective of the cable retaining yoke. Fig. 5 is a plan view of the blank from which the 35 pulley supporting frame is formed. Fig. 6 is a vertical section through the outer looped end of the pulley supporting frame showing the manner in which the cable retaining loop is held against movement relative to the supporting frame.

40 By referring to the drawings it will be seen that 1 designates the pulley supporting frame which is formed of an elongated blank sheet of material being bent intermediate its ends to constitute a hook engaging loop 2 at its rear end. The frame 1 comprises a pair of parallel side portions, which side portions are provided with apertures 3 adjacent their outer ends for the purpose 45 of receiving the pintle pin 4 which is adapted to support the pulley 5. It should be understood that the parallel side portions of the frame 1 are brought close together to constitute a reduced neck portion 6 as is 50 illustrated in Fig. 3 for the purpose of holding the frame 1 upon a hook or other suit-

able support such as is illustrated in dotted lines in Fig. 1.

The outer ends of the parallel side portions of the frame 1 are rolled so as to produce the elongated cylindrical portions 7, and within these cylindrical portions 7 is placed an elongated elliptical link 8 formed of wire or other suitable material. The link 8 is adapted to straddle the pulley 5 as is 60 illustrated in Fig. 1 and is held in such a position as to allow the pulley 5 to readily rotate upon the frame 1 without interfering with the link 8. It should be understood that the link 8 projects above and below 70 the pulley 5 at a sufficient distance to constitute means for preventing the cable 9 adapted to pass around the pulley 5 from jumping from the pulley and becoming entangled with the frame 1 or otherwise disengaged 75 from the pulley.

By carefully considering Figs. 1 and 6 it will be seen that the cylindrical portions 7 are punched inwardly so as to produce inwardly extending tongue portions 10 at their 80 respective ends and upon each side for gripping into the link 8 and constitute efficient means for holding the link 8 against longitudinal movement within the cylindrical portions 7 of the frame 1. It will be seen 85 that the inwardly bent tongues 10 will constitute a very efficient means for biting into the notch portions 11 which are formed in the link 8 by punching the tongues 10 into the link. These tongues will constitute an 90 efficient means as stated above and as will be clearly understood for holding the link against longitudinal movement within the cylindrical portions 7 or against transverse movement relative to the frame 1.

95 From the foregoing description it will be seen that a very simple and efficient, as well as a durable device has been produced for holding the link 8 in engagement with the frame 1, thereby greatly facilitating the 100 holding of the cable upon the pulley 5.

Having thus described the invention what is claimed as new, is:—

A device of the class described comprising 105 a frame, a pulley carried thereby, said frame provided with parallel side portions having bowed cylindrical portions at their outer ends and extending at an angle to said frame, a retaining link comprising an elongated elliptical body portion fitting within 110 said cylindrical portions and straddling said pulley for constituting a retaining means

for holding a cable upon said pulley, said cylindrical portions provided with inwardly punched tongues upon their respective sides for biting into said retaining link for locking said link against transverse movement relative to said frame.

In testimony whereof I hereunto affix my signature in presence of two witnesses.

CHARLES L. BLODGETT.

Witnesses:

FRANK W. BLODGETT,
ARTHUR L. MULVANY.
